UNITED STATES PATENT OFFICE.

GEORGE M. J. MACKAY, OF SCHENECTADY, NEW YORK, ASSIGNOR TO GENERAL ELECTRIC COMPANY, A CORPORATION OF NEW YORK.

ELECTRIC OSCILLATOR.

1,337,933.

Specification of Letters Patent. Patented Apr. 20, 1920.

Application filed January 27, 1918. Serial No. 74,594.

To all whom it may concern:

Be it known that I, GEORGE M. J. MACKAY, a subject of the King of Great Britain, residing at Schenectady, county of Schenectady, State of New York, have invented certain new and useful Improvements in Electric Oscillators, of which the following is a specification.

The present invention comprises an apparatus for producing high frequency electric oscillations from either direct current or low frequency alternating current, and it is the object of my invention to provide a means for generating oscillations which is 10 of greater stability than arc oscillators heretofore used, and to generate high frequency waves substantially free from harmonics, and of relatively large power. The electrodes being substantially non-consuming 15 and not being brought into contact when the arc is started, the arc gap may be accurately fixed.

The apparatus embodying my invention comprises an oscillating circuit containing 20 electrodes, one of which consists of refractory material operable at incandescence above about 2000° C. in a gas substantially inert with respect to the incandescent electrode and at a pressure high enough to suppress electrical disintegration of the electrodes. My invention will be pointed out 25 with greater particularity in the appended claims taken in connection with the appended drawings and the accompanying 30 description.

Figure 1 shows an arc device with a diagram of electrical connections, and Fig. 2 shows a modification in which the arc of the oscillator is subjected to a magnetic field.

Referring to Fig. 1 of the drawings, the arc is produced in an envelop 1 between a cathode 2 and an anode 3 connected respectively by conductors 4, 5 to a source of 40 energy 6. The cathode comprises a coiled conductor 7, and a more massive pointed arcing tip 8 which is located close to and in good thermal relation to the coil 7. The cathode consists preferably of ductile tungsten but other refractory materials incandescent at a temperature above about 2000° C. may be used, for example, tantalum. A heating current may be conveyed to the cathode by the conductors 9, 10 which may 50 also consist of tungsten, and which are

sealed in the usual way into a stem 11. The anode 3 and its supporting stem 12, preferably consist of tungsten but various conductive materials may be used, for example, carbon, copper, iron or other metals. 60 The anode should preferably have a heat-dissipating capacity large enough to enable it to operate continuously below the temperature at which appreciable electron emission occurs, say about 700 to 800° C. The 65 envelop after having been evacuated of air and deprived of water vapor is filled with a dry gas having little or no chemical affinity for the electrode material when at the operating temperature. Preferably I 70 employ a gas such as hydrogen in which the arc drop, or voltage consumption is relatively high but various other gases, for example, nitrogen, carbon monoxide, argon, neon, mercury vapor, or mixtures of the 75 above may be used. When using mercury vapor the size and heat dissipating capacity of the envelop should be adjusted to keep the envelop at a temperature high enough to maintain the mercury vapor at the desired pressure.

The pressure of the gas may vary within wide limits but should in all events be high enough to suppress electrical disintegration of the electrodes. Ordinarily the gaseous 85 pressure should be materially in excess of about 50 millimeters of mercury, and preferably high enough to cause most of the energy supplied to the arc to be expended in the gas. I have used pressures of about 90 two-thirds of an atmosphere with the envelop at room temperature with good success. Pressures much above atmospheric pressure endanger the envelop particularly when the gas is subjected to variable heat- 95 ing.

Connected in shunt with the arc is a resonant circuit containing an adjustable condenser 13 and an adjustable inductance coil 14. There is included also in this circuit 100 the primary coil 15 of a transformer loosely coupled with a coil 16, feeding a consumption circuit 17. The energy supply circuit 4, 5 also contains a resistance 18 and inductances 19, 20.

When starting the device the cathode is first heated from any convenient source, as for example, a transformer 21. The switch 22 may then be closed and an arc will pass between the electrodes 2, 3. The heating 110

current may be cut off when the cathode is at incandescence and the arc will continue to pass from the arcing tip 8 to the anode, thus the necessity of bringing the electrodes 5 into contact is avoided. No wandering of the arc over the cathode occurs with the described construction thereby insuring regularity in the oscillations.

By proper adjustment of the capacity and 10 inductance in the oscillation circuit 23 a desired high frequency current may be obtained. For example, with a gap of about $\frac{1}{2}$ millimeter in hydrogen at about atmospheric pressure, I have started in this manner 15 an arc between tungsten electrodes at about 250 volts which continued to operate with about 50 volts arc drop. With .05 micro farads capacity and 0.5 millihenries inductance in shunt with the arc a current 20 of about 8 amperes was obtained in the oscillation circuit 23 with a frequency of about 32,000. In general the frequency may be obtained approximately from the relationship

$$25 \quad N = \frac{1}{2\pi\sqrt{LC}}$$

As both the cathode and the anode are substantially non-consuming and as the electrodes are permanently located in the device 30 in a fixed position with respect to each other, the length of the arc gap remains constant during the operation of the device.

When coupled to an antenna circuit in the usual way frequencies of 100,000 and higher 35 have been obtained with a current of 8 amperes especially suitable for telephonic communication. The distance between the electrodes may be varied with the supply voltage, for example, with a potential of 750 40 volts the gap may be 6 or 7 millimeters in length.

In some cases greater efficiencies may be obtained by applying to the arc a transverse magnetic field as illustrated in Fig. 2. The 45 field may be generated by a winding 24

located opposite the arc gap and connected in series with the generator 6 supplying the arc.

What I claim as new and desire to secure by Letters Patent of the United States, is:— 50

1. An apparatus adapted to generate high frequency oscillations comprising the combination of a resonant circuit and an electric discharge device connected thereto, said device consisting of a sealed envelop containing a gaseous filling at a substantial pressure, a substantially non-consuming cathode adapted to operate at incandescence, and an anode, the gap intervening between said electrodes being substantially constant whereby 55 the oscillations produced are regular and largely free from harmonics. 60

2. An apparatus adapted to generate high frequency oscillations comprising the combination of a resonant circuit and a discharge device connected thereto comprising a sealed envelop, a tungsten cathode, an anode and a filling of gas inert with respect to tungsten having a pressure of at least about 50 millimeters of mercury, the gap intervening between said electrodes being substantially constant whereby oscillations largely free from harmonics may be produced. 65

3. An apparatus adapted to generate regular high frequency oscillations substantially free from harmonics comprising the combination of an oscillating circuit and an electric discharge device connected thereto said device comprising an anode, a tungsten 70 cathode having a pointed arcing tip and located in fixed arcing relation to said anode, and a filling of gas inert with respect to said electrodes having at operating temperatures a pressure high enough to materially 75 suppress disintegration of the electrodes. 80

In witness whereof, I have hereunto set my hand this 25th day of January, 1916.

GEORGE M. J. MACKAY.
